Aikoper heater May 26, 2020 found on Oct. 17, 2022 at: <https://www.amazon.com/Electric-Heaters-Portable-Thermostat-Heating/dp/B0895QVCYC/> (Year: 2020).*Primary Examiner — Dana K Weiland*Assistant Examiner* — Jonathan E Fiencke(74) *Attorney, Agent, or Firm* — Jose Cherson Weissbrot(57) **CLAIM**

The ornamental design for a heater, as shown and described.

DESCRIPTION

FIG. 1 is a perspective view of a heater, showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of area 9 circumscribed within FIG. 1; and,

FIG. 10 is an enlarged detail view of area 10 circumscribed within FIG. 2.

The evenly spaced broken lines depict portions of the heater that form no part of the claimed design. The dot dash dot broken lines denote the boundaries of the detail areas and form no part of the claim.
